APPARATUS FOR RECTIFYING ELECTRIC CURRENT

Howard I. Morris, Lakewood, Ohio, assignor of one-third to Carl M. Yoder and one-third to Harvey O. Yoder, both of Lakewood, Ohio

Application December 30, 1940, Serial No. 372,253

8 Claims. (Cl. 172—281)

This invention relates to apparatus for and process of rectifying alternating current by mechanical means into direct current. In all apparatus for rectifying alternating current, of which I have knowledge, it has been found necessary to use specially constructed transformers and/or various other complicated equipment, whereas in my invention devices and equipment of this character are entirely eliminated, whereby simplicity in construction and economy in cost and up-keep results.

One object of the invention is to provide an improved apparatus of this character that is relatively simple in construction and the parts of which are readily assembled and adjusted for cooperation to insure efficient operation.

Another object of the invention is to provide an improved apparatus of this character which may be adapted to rectifying alternating current of different phases into direct current.

Another object of the invention is to provide an improved mechanism constructed and arranged to increase or decrease the frequency of alternating current flowing from a power supply.

Another object of the invention is to provide an improved mechanism for rectifying alternating current into direct current, said mechanism being constructed to provide an unbroken direct current.

Another object of the invention is to provide an improved apparatus wherein means are provided for rectifying the supplied alternating current into direct current and then changing the direct current to alternating current having any desired predetermined frequency.

A further object of the invention is to provide an improved process of rectifying alternating current having any predetermined phase into direct current.

Other objects of the invention will be apparent to those skilled in the art to which my invention relates from the following description taken in connection with the accompanying drawings, wherein

Fig. 1 is a plan view of an apparatus embodying my invention.

Fig. 2 is a side elevation.

Fig. 3 is a fragmentary section on the line 3—3 of Fig. 4.

Fig. 4 is a section on the line 4—4 of Figs. 2 and 3; this view being enlarged as compared to Fig. 2.

Fig. 5 is a section on the line 5—5 of Figs. 2 and 3.

Fig. 6 is a section on the line 6—6 of Fig. 7.

Fig. 7 is a section on the line 7—7 of Figs. 2 and 3.

Figs. 8, 10, 12, 14, 16, 18, 20, 22, 24, 26, 28 and 30 are semi-diagrammatic or developed views of the commutator members and associated parts showing the commutator members in their respective positions through one complete cycle.

Figs. 9, 11, 13, 15, 17, 19, 21, 23, 25, 27, 29 and 31, are graphs of the alternating current corresponding to Figs. 8, 10, 12, 14, 16, 18, 20, 22, 24, 26, 28 and 30, respectively, the angle of one phase in each position of the adjacent commutator member being indicated by a dotted line.

Fig. 32 is a fragmentary section on the line 15 32—32 of Fig. 33.

Fig. 33 is a fragmentary section on the line 33 of Figs. 2 and 32.

Fig. 34 is a section on the line 34—34 of Fig. 35. Fig. 35 is a section on the line 35—35 of Figs. 20 2 and 34.

Figs. 36 and 37 are diagrammatic views illustrating the positions of the collector members in changing the direct current to alternating current.

25 In the apparatus herein disclosed, for the purpose of illustrating one embodiment of the invention, I provide an arrangement wherein a three phase alternating current is rectified into direct current, but it will be understood that by 30 changing the number of commutators and/or the relationship of the segments thereon, an alternating current of different phase may be rectified into direct current.

In the drawings, 1 indicates a base or support 35 for a plurality of spaced standards 2, 2a, 2b, 2c, 2d and 2e, each provided at their upper ends with aligned tubular members 2', the inner walls of which form bearings for a shaft 3; however, I may provide in the members 2' suitable anti-friction bearings for the shaft 3. One end of the shaft 3 is suitably connected to and driven by the shaft 4 of a synchronous motor 5 suitably supported on the base 1. 6, 7, 8, indicate the leads of a three-phase alternating current, which is to be rectified as hereinafter set forth, the current being supplied from any desired source.

9 indicates sleeves keyed to the shaft 3 (see Figs. 3, 4, 5, 6 and 7), one thereof disposed between each of the tubular members 2' and the adjacent tubular member 2' for the standards 2, 2a, 2b and 2c, each sleeve 9 preferably being of a length to fit between and abut against the opposed faces of the adjacent tubular members 2', whereby the latter prevent endwise movement 50 of the sleeve on the shaft 3. The opposite end

portions of each sleeve 8 is externally threaded to receive nuts 10 between which is secured a commutator member 11, whereby the latter is rotated with the shaft 3. The sleeves 8 and nuts 10 are formed of suitable insulation material.

In the arrangement above described, it will be understood that I provide three commutator members, designated 11, 11a, 11b (for purpose of later identification), due to the fact that the alternating current supplied by the leads 6, 7, 8, is of the three-phase type.

As the commutator members 11 and parts associated therewith, respectively, are similar in construction, one assembly thereof only is illustrated—namely, the one designated 11 (see Figs. 3, 4, 5, 6 and 7)—and needs to be described for a complete understanding of the invention.

The commutator member 11 comprises a ring 12 to which are integrally connected diametrically related segments 13, the latter being separated by sections of suitable insulation 14, the outer ends of the segments 13 and adjacent ends of the insulation sections 14 being enlarged for engagement by brushes 15 to which reference will later be made. The sections of insulation 14 are secured to the adjacent sleeve 8 by screws 14a. 16, 16, indicate a pair of brushes in diametrical relation and engaging the ring 12, the brushes which engage ring 12 of commutator 11 being connected by lead 12a to main 6, the brushes 16 which engage ring 12 of commutator member 11a being connected by lead 12b to main 7 and the brushes 16 which engage ring 12 of commutator member 11b being connected by lead 12c to main 8. Each brush 16 is slidably mounted in a guide member 17 mounted on a pin 18, which is supported by an arm 19, the latter being integrally connected to a collar 20 seated in an annular recess 2' formed in the end of the adjacent tubular member 2' (see Fig. 3). Each brush 16 is pressed inwardly toward the ring 12 by a spring operated arm 21a. The collar 20 is preferably secured to the adjacent tubular member 2' by a set screw 20a.

I provide four brushes 15 in uniformly spaced relation about the commutator member 11, each brush being mounted similarly to the brushes 15 on an arm 22 which is formed integrally with a collar 23, the latter being seated in an annular recess 24 formed in the end portion of the adjacent tubular member 2' and fixed thereto by a suitable set screw (not shown).

For identification purposes, the ring of commutator member 11 is designated 12, the segments thereof are designated 13, 13a and the adjacent insulation sections are designated 13', 13a'; the ring of commutator member 11a is designated 12a, the segments thereof are designated 13b, 13b', and the adjacent insulation sections are designated 13b'', 13b'''; and the ring of commutator member 11b is designated 12b, the segments thereof are designated 13c, 13c' and the adjacent insulation sections are designated 13c'', 13c'''; also, the brushes for the commutator member 11 are designated 15, 15a, 15b, 15c; the brushes for commutator member 11a are designated 15', 15a', 15b', 15c'; and the brushes for commutator member 11b are designated 15'', 15b'', 15c''.

As shown in Figs. 8, 10, 12, 14, 16, 18, 20, 22, 24, 26, 28 and 30, (1) brushes 15, 15a, are connected by leads 25, 25', to out-put direct current main 26—one side of the circuit, whereas brushes 15b, 15c, are connected by leads 25a, 25a' to out-

put direct current main 28a—the other side of the circuits; (2) brushes 15', 15a', are connected by leads 25b, 25b', to main 26, whereas brushes 15b', 15c', are connected by leads 25c, 25c', to main 26a; and (3) brushes 15'', 15a'', are connected by leads 25d, 25d', to main 26, whereas the brushes 15b'', 15c'' are connected by leads 25e, 25e', to the main 26a.

Fig. 8 shows the position of the commutator members 11, 11a, 11b, represented by the phase angle A of the current in lead 6 (Fig. 9). In this view, (1) as indicated by the arrows a, a', current from direct current main 26 is flowing through leads 25, 25', brushes 15, 15a, segments 13, 13a, ring 12, brushes 16 to lead 6; whereas since brushes 15b, 15c are engaging the insulation sections 13', 13a' the circuit in direct current main 26a, indicated by arrows a'', through commutator member 11 is open; (2) since the phase angle is zero for the current in lead 7, the brushes 15', 15a', 15b', 15c', are engaging with the insulation sections 13b'', 13b''', and therefore no current is flowing through commutator member 11a in either direction; (3) and as indicated by the arrows a'', a''', the current in lead 8 is flowing through brushes 16, ring 12b, segments 13c, 13c', brushes 15b'', 15c'', leads 25e, 25e', and direct current main 26a, whereas since brushes 15'', 15a'', are engaging the insulation sections 13c'', 13c''', the current from the negative side of the direct current main 26 is open through commutator member 11b.

Fig. 10 shows the position of the commutator members 11, 11a, 11b, represented by the phase angle B of the current in lead 6 (Fig. 11), the voltage decreasing in lead 6 and increasing in lead 7. In this view, (1) as indicated by the arrows a, a', a portion of the current in direct current main 26 is flowing through leads 25, 25', brushes 15, 15a, segments 13, 13a, ring 12, brushes 16 to lead 6 (the positive side of the direct current through main 26a being open as brushes 15b, 15c are engaging the insulation sections 13', 13a'); (2) as indicated by the arrows a', b, a portion of the current in direct current main 26 is flowing through leads 25b, 25b', brushes 15', 15a', segments 13b, 13b', ring 12a, brushes 16 and lead 7 (the circuit of the direct current main 26a through commutator member 11a being open as brushes 15b', 15c', are engaging the insulation sections 13b'', 13b'''); and (3) as indicated by the arrows a'', a''', current in lead 8 is flowing through brushes 16, ring 12b, segments 13c, 13c', brushes 15b'', 15c'', leads 25e, 25e' to main 26a.

Fig. 12 shows the position of the commutator members 11, 11a, 11b, represented by the phase angle C (zero phase angle) of the current in lead 6 (Fig. 13). In this view, (1) the circuit in both direct current mains 26, 26a, is open through commutator member 11, since the brushes 15, 15a, 15b, 15c, are engaging the insulation sections and therefore no current is flowing in either direction through commutator member 11; (2) as indicated by the arrows a', b, current is flowing through the direct current main 26a, leads 25b, 25b', brushes 15', 15a', segments 13b, 13b', ring 12a to lead 7, whereas the circuit in the main 26 through commutator member 11a is open since brushes 15b', 15c', are engaging the insulation sections 13b'', 13b'''; and (3) as indicated by the arrows a'', a''', current is flowing from lead 8, through brushes 16, segments 13c, 13c', brushes 15b'', 15c'', leads 25e, 25e', to direct current main 26a, the circuit in direct current main 26 through commutator member 11b being open since

brushes 15'', 15a'', are engaging the insulation sections 13c'', 13c'''.

Fig. 14 shows the position of the commutator members 11, 11a, 11b, represented by the phase angle D of the current in lead 6 (Fig. 15). In this view, (1) as indicated by the arrows a, a^x, current is flowing from lead 6 through brushes 16, ring 12, segments 13, 13a, brushes 15b, 15c, leads 25a, 25a' to direct current main 26a, whereas the circuit in direct current main 26 is open through commutator member 11 since the brushes 15, 15a, are engaging the insulation sections 13', 13a'; (2) as indicated by the arrows a', b, current from direct current main 26 is flowing through leads 25b, 25b', brushes 15', 15a', segments 13b, 13b', ring 12a and brushes 16 to lead 7, the circuit in direct current main 26a through commutator member 11a being open since the brushes 15b', 15c', are engaging the insulation sections 13b'', 13b''' and (3) as indicated by the arrows a^x, a^x', a portion of the current is flowing from lead 8 through brushes 16, ring 12b, segments 13c, 13c', brushes 15b'', 15c'', leads 25e, 25e' to direct current main 26a, the circuit from direct current main 26 through commutator member 11b being open since brushes 15'', 15a'', are engaging the insulation sections 13c'', 13c'''.

Fig. 16 shows the position of the commutator members 11, 11a, 11b, represented by the phase angle E of the current in the lead 6 (Fig. 17). In this view, (1) as indicated by the arrows a, a^x, current is flowing from lead 6 through brushes 16, ring 12, segments 13, 13a, brushes 15b, 15c, leads 25a, 25a', to direct current main 26a, whereas the circuit in direct current main 26 through commutator member 11 is open since brushes 15, 15a, are engaging the insulation sections 13', 13a'; (2) as indicated by the arrows a', b, current from the direct current main 26 is flowing through leads 25b, 25b', brushes 15', 15a', segments 13b, 13b', ring 12a and brushes 16 to lead 7, the circuit from direct current main 26a through commutator member 11a being open since brushes 15b', 15c', are engaging the insulation sections 13b'', 13b''' and (3) since the phase of the current in lead 8 is at zero angle, the brushes 15'', 15a'', 15b'', 15c'', are engaging the insulation sections of commutator 11b and therefore no current is flowing in either direction therethrough.

Fig. 18 shows the position of the commutator members 11, 11a, 11b, as represented by the phase angle F of current in lead 6 (Fig. 19). In this view, (1) as shown by the arrows, a, a^x, current is flowing from lead 6 through brushes 16, ring 12, segments 13, 13a, brushes 15b, 15c, leads 25a, 25a', to direct current main 26a, the circuit in direct current main 26 through commutator 11 being open since the brushes 15, 15a, are engaging insulation sections 13', 13a'; (2) as indicated by the arrows, a, b, a portion of the current in direct current main 26 is flowing through leads 25b, 25b', brushes 15', 15a', segments 13b, 13b', ring 12a, brushes 16 to lead 7, the circuit in direct current main 26a through commutator member 11a being open since brushes 15b', 15c', are engaging the insulation sections 13b'', 13b''' and (3) as indicated by the arrows a, a^x, a portion of the current in direct current main 26 is flowing through leads 25d, 25d', brushes 15'', 15a'', segments 13c, 13c', ring 12b, brushes 16 to lead 8, the circuit in direct current main 26a through commutator member 11b being open since brushes

15b'', 15c'', are engaging the insulation sections 13c'', 13c'''.

Fig. 20 shows the position of the commutator members 11, 11a, 11b, represented by the phase angle G of the current in lead 6 (Fig. 21). In this view, (1) as indicated by the arrows a, a^x, current is flowing from lead 6 through brushes 16, ring 12, segments 13, 13a, brushes 15b, 15c, leads 25a, 25a', to direct current main 26a, the circuit in direct current main 26 through commutator member 11 being open since the brushes 15, 15a, are engaging the insulation sections 13', 13a'; (2) as the current in lead 7 is at zero angle phase, the brushes 15', 15a', 15b', 15c', for commutator member 11a are engaging the insulation sections 13b'', 13b''', no current is flowing in either direction therethrough; and (3) as indicated by the arrows a, a^x, current is flowing from direct current main 26 through leads 25d, 25d', brushes 15'', 15a'', segments 13c, 13c', ring 12b, brushes 16 to lead 8, the circuit in direct current main 26a through commutator member 11b being open since brushes 15b'', 15c'', are engaging the insulation sections 13c'', 13c'''.

Fig. 22 shows the position of the commutator members 11, 11a, 11b, represented by the phase angle H of the current in lead 6 (Fig. 23). In this view, (1) as indicated by the arrows a, a^x, a portion of the current is flowing from lead 6 through brushes 16, ring 12, segments 13, 13a, brushes 15b, 15c, leads 25a, 25a', to direct current main 26a, the circuit in direct current main 26 through the commutator member 11 being open since the brushes 15, 15a, are engaging the insulation sections 13', 13a'; (2) as indicated by the arrows b, a^x, a portion of the current is flowing from lead 7 through brushes 16, ring 12a, segments 13b, 13b', brushes 15b', 15c', leads 25c, 25c', to direct current main 26a, the circuit in direct current main 26 through commutator member 11a being open since the brushes 15', 15a', are engaging the insulation sections 13b'', 13b'''; and (3) as indicated by the arrows a, a^x, current is flowing from direct current main 26 through leads 25d, 25d', brushes 15'', 15a'', segments 13c, 13c', ring 12b and brushes 16 to lead 8, the circuit in direct current main 26a through commutator member 11b being open since brushes 15b'', 15c'' are engaging the insulation sections 13c'', 13c'''.

Fig. 24 shows the position of the commutator members 11, 11a, 11b, represented by the phase angle I (zero phase angle) of the current in lead 6 (Fig. 25). In this view, (1) the brushes 15, 15a, 15b, 15c, are engaging the insulation sections 13', 13a' so that no current is flowing through commutator member 11 in either direction; (2) as indicated by the arrows a^x, b, current is flowing from lead 7, through brushes 16, ring 12a, segments 13b, 13b', brushes 15b', 15c', leads 25c, 25c', to direct current main 26a, the circuit in direct current main 26 through commutator 11a being open since brushes 15'', 15a'', are engaging the insulation sections 13b'', 13b'''; and (3) as indicated by the arrows a, a^x, current is flowing from direct current main 26 through leads 25d, 25d', brushes 15'', 15a'', segments 13c, 13c', ring 12b and brushes 16 to lead 8, the circuit in direct current main 26a through commutator member 11b being open since brushes 15b'', 15c'', are engaging the insulation sections 13c'', 13c'''.

Fig. 26 shows the position of the commutator members 11, 11a, 11b, represented by the phase angle J of the current in lead 6 (Fig. 27). In this

view, (1) as indicated by the arrows a , a' , a portion of the current in direct current main 26 is flowing through leads 25 , $25'$, brushes 15 , $15a$, segments 13 , $13a$, ring 12 and brushes 16 to lead 6 , the circuit in direct current main $26a$ through commutator member 11 being open since brushes $15b$, $15c$, are engaging the insulation sections $13'$, $13a'$; (2) as indicated by the arrows b , a^x , the current is flowing from lead 7 through brushes 16 , ring $12a$, segments $13b$, $13b'$, brushes $15b'$, $15c'$, and leads $25c$, $25c'$, to direct current main $26a$, the circuit in direct current main 26 through commutator $11a$ being open since brushes $15'$, $15a'$, are engaging the insulation sections $13b''$, $13b'''$; and (3) as indicated by the arrows a , a^x , a portion of the current in direct current main 26 is flowing through leads $25d$, $25d'$, brushes $15''$, $15a''$, segments $13c$, $13c'$, ring $12b$ and brushes 16 to lead 8 , the circuit in direct current main $26a$ through commutator member $11b$ being open since brushes $15b''$, $15c''$, are engaging the insulation sections $13c''$, $13c'''$.

Fig. 28 shows the position of the commutator members 11 , $11a$, $11b$, represented by the phase angle K of current in lead 6 (Fig. 29). In this view, (1) as indicated by the arrows a , a' , current is flowing from the direct current main 26 through leads 25 , $25'$, brushes 15 , $15a$, segments 13 , $13a$, ring 12 and brushes 16 to lead 6 , the circuit in direct current main $26a$ through commutator member 11 being open since the brushes $15b$, $15c$, are engaging the insulation sections $13'$, $13a'$; (2) as indicated by the arrows b , a^x , current is flowing from lead 7 through brushes 16 , ring $12a$, segments $13b$, $13b'$, brushes $15b'$, $15c'$, and leads $25c$, $25c'$, to the direct current main $26a$, the circuit in direct current main 26 through commutator member $11a$ being open since the brushes $15'$, $15a'$, are engaging the insulation sections $13b''$, $13b'''$; and (3) as the phase angle of lead 8 is zero, the brushes $15''$, $15a''$, $15b''$, $15c''$, are engaging the insulation sections $13c''$, $13c'''$, and therefore no current is flowing through the commutator member $11b$ in either direction.

Fig. 30 shows the position of the commutator members 11 , $11a$, $11b$, represented by the phase angle L in the current of the lead 6 (Fig. 31). In this view, (1) as indicated by the arrows a , a' , current is flowing from the direct current main 26 through leads 25 , $25'$, brushes 15 , $15a$, segments 13 , $13a$, ring 12 and brushes 16 to lead 6 , the circuit in direct current main $26a$ through commutator member 11 being open since the brushes $15b$, $15c$, are engaging the insulation sections $13'$, $13a'$; (2) as indicated by the arrows b , a^x , a portion of the current is flowing from lead 7 through brushes 16 , ring $12a$, segments $13b$, $13b'$, brushes $15b'$, $15c'$, and leads $25c$, $25c'$, to direct current main $26a$, the circuit in direct current main 26 through the commutator member $11a$ being open since brushes $15'$, $15a'$, are engaging the insulation sections $13b''$, $13b'''$; and (3) as indicated by the arrows a^x , a^x , a portion of the current is flowing from lead 8 through brushes 16 , ring $12b$, segments $13c$, $13c'$, brushes $15b''$, $15c''$, and leads $25e$, $25e'$, to direct current main $26a$, the circuit in direct current main 26 through commutator member $11b$ being open since brushes $15''$, $15a''$, are engaging the insulation sections $13c''$, $13c'''$.

It will be noted that in each of the Figs. 11, 13, 15, 17, 19, 21, 23, 25, 27, 29 and 31, the phase angle is shown advanced approximately 30° relative to the phase angle shown in the previous view; accordingly, the advance of the phase angle 30°

beyond that shown in Fig. 31 would coincide with the phase angle shown in Fig. 9, so that these views and the corresponding views of the commutator members 11 , $11a$, $11b$, illustrate one complete cycle.

In the foregoing described construction, each segment on the commutator 11 is disposed approximately 30° rearwardly of one of the segments on the commutator $11b$ and each segment on the commutator $11a$ has the same relation to a segment on the commutator 11 and each segment on the commutator $11b$ has the same relation to a segment on the commutator $11a$. In rectifying a single phase alternating current, the same form of construction would be employed, except that only two commutators would be required and each segment on each thereof would be disposed 90° rearward of a segment on the other commutator.

It is also to be noted that notwithstanding the reversal of direction of current in the leads 6 , 7 , 8 , that two thereof are always connected to one side of the direct current circuit and the remaining lead is always connected to the other side of said circuit, except when the phase angle of each lead is at zero. While I have indicated the main 26 to be negative and main $26a$ to be positive, their polarity may be reversed.

From the foregoing description it will be noted

(a) that I provide sets of contacts between each alternating current main and the direct current mains, one set consisting of segments connected to the alternating current main, and separate sets (each consisting of brushes), with which the segments alternately engage, connected to the direct current mains, respectively, the alternate engagement of the segments with the said separate sets of contacts being synchronized with the reversal of current flow or polarity in the alternating current main (1) to connect it to that direct current main having the same polarity and (2) to disconnect the alternating current main from both direct current mains when the phase angle is zero in the alternating current main and

(b) that the sets of contacts connected to the alternating current mains are co-operatively related so that in each complete cycle (irrespective of the frequency of the supplied current) successive positive phases thereof are connected to the direct current positive main and the successive negative phases thereof are connected to the direct current negative main, to produce in the latter mains an unbroken direct current circuit.

It will further be noted that my apparatus is relatively simple and may be built to operate under any predetermined conditions, independently of the voltage impressed on the leads 6 , 7 , 8 . The apparatus has many advantages since direct current is employed in many instances where only alternating current is available.

27 indicates as an entirety an attachment for the apparatus by means of which the resultant direct current is converted into alternating current, such operation being effected by mechanical means. By means of the apparatus already described and the attachment 27, I am able to provide an alternating current having a different frequency (higher or lower), as compared to that of the current supplied by the

leads 6 , 7 , 8 , by a simple form of mechanism. In the arrangement shown (see Figs. 1, 2, 32 to 37, inclusive) the attachment 27 operates to provide a high frequency alternating current. Accordingly, by means of a switch 28 in the direct current mains 26 , $26a$, the direct current may

be supplied to leads 26', 26a'' which are connected to the attachment 21 or supplied to leads 26x, 26x', which may be connected to any suitable apparatus.

As shown, the shaft 3 is extended through the tubular members 2' of the standards 2d, 2e (Figs. 1, 2 and 32), for support therein and has secured to it two collector members 29, 29a, the former being arranged between the standards 2c and 2d and the latter being arranged between the standards 2d and 2e. This arrangement insures a simplified, unitary form of construction.

The collector members 29, 29a, and the parts associated with each, are similar in construction, so that only one thereof (designated 29—see Figs. 32, 33, 34, 35) needs to be described, although like parts associated with the member 29a will be designated by the same reference characters. The collector member 29 consists of a ring 30 integrally connected to a plurality of segments 30a (preferably six segments as shown in Fig. 33), which are separated by sections of suitable insulation material 31, the ring 30, segments 30a and sections 31 being suitably secured to a sleeve 32 formed of suitable insulation material and keyed to the shaft 3 and preferably of a length to abut the opposed ends of the adjacent tubular members 2'. The sleeve 32 is externally threaded adjacent its opposite ends to take ring nuts 32a which are tightened against the outer side wall of the ring 30 and free ends of the segments 30a and sections 31; whereas the inner ends of the sections 31 are secured to the sleeve 32 by screws 33, which are mounted in the cut-aways 33a formed in the sections 31 to dispose their heads below or inwardly of the outer surfaces of the ring 30 and segments 30a. 34, 34', indicate series of brushes arranged to engage the segments 30a and sections 31 as the member 29 is driven by the shaft 3, one series being connected to one direct current main 26' and the other series of brushes being connected to the direct current main 26a'. The brushes of one series are staggered with reference to the brushes of the other series, but the brushes of each series (which correspond in number to the number of segments) are spaced so as alternately to engage all of the segments simultaneously and all of the insulation sections 31 simultaneously. A collar 35, which is seated on the tubular member 2' for the standard 2d and fixed thereto by a set screw 35a, is provided with arms 36 terminating in hollow bosses 37 and the latter in turn support a pair of pins 38 which extend through and support an annulus 39. The pins 38 and additional pins 38' mounted in the annulus 39 (see Fig. 32) support the brushes 34, whereas separate pins 38'' mounted in the annulus similarly to the pins 38' and disposed between the latter, support the brushes 34', whereby the brushes 34, 34', engage the segments 30a. A collar 40, which is seated on the tubular member 2' for the standard 2c and fixed thereto by a set screw 40a, is provided with arms 41 terminating in hollow bosses 42 and the latter in turn support a pair of pins 43. The pins 43 support a pair of brushes 44 which engage the ring 30.

Referring to Fig. 36 it will be noted that the collector members 29, 29a, are angularly related on the shaft 3 so that at the time the brushes 34 adjacent to collector member 29 are engaging the segments 30a thereof, the brushes 34 adjacent to collector member 29a are en-

gaging the insulation sections 31 thereof, whereas at the time the brushes 34' adjacent to collector member 29 are engaging the insulation sections 31 thereof, the brushes 34' adjacent to collector member 29a are engaging the segments 30a thereof; accordingly in the position shown, current in the main 26' is flowing through the brushes 34, segments 30a of collector member 29, the adjacent ring 30 and brushes 44 to out-put lead 45 and current in out-put lead 45' is flowing therefrom through brushes 44, ring 30 of collector member 29a, the adjacent segments 30a and brushes 34' to direct current main 26a'. Referring to Fig. 37, which shows the collector members 29, 29a, rotated to the succeeding position, the series of brushes 34, 34' adjacent each member are in engagement with the insulation sections 31 and segment 30a, respectively; accordingly, the current in out-put main 45 is flowing in the reverse direction through brushes 44, ring 30 of collector member 29, brushes 34' to direct current lead 26' and current in direct current lead 26a' is flowing therefrom through brushes 34, segments 30a of collector member 29a, ring 30 and brushes 44 to out-put main 45'. It will thus be seen that as the collector members 29, 29a, rotate, the direct current mains 26', 26a' are alternately connected through the series of brushes 34, 34', and collector members 29, 29a, to the out-put mains 45, 45'; that is, (a) when the brushes 34 related to collector member 29 are engaging its segments 30a, the brushes 34' related to collector member 29a are engaging its segments 30a and (b) when the brushes 34' related to collector member 29 are engaging its segments 30a, the brushes 34 of collector member 29a are engaging its segments 30a and (c) as all of the brushes 34 related to collector members 29, 29a, are connected to direct current main 26' and all of the brushes 34' related to collector members 29, 29a, are connected to direct current main 26a', it will be seen that as the shaft 3 rotates the direct current in mains 26', 26a', is converted into alternating current 45 in the out-put mains 45, 45', the frequency of which depends upon the number of segments 30a provided in the collector members 29, 29a, and brushes for engagement therewith and the speed of rotation of the shaft 3.

It will be understood that the collector members 29, 29a may be mounted on a separate shaft driven independently of the shaft 3; also that the attachment 21 may be utilized to convert direct current, which is supplied from any suitable source into alternate current of any desired frequency.

The machine as shown is designed for use where relatively low voltage is impressed on the alternating current mains, so that danger of arcing is reduced to a minimum or entirely eliminated. Where a high voltage is supplied, the diameters of the rotary members may be increased to insure a quick break between each brush and each segment. Also, capacitors or other equivalent apparatus may be employed to absorb the arc, if found necessary.

To those skilled in the art to which my invention relates, many changes in construction and widely differing embodiments and applications of the invention will suggest themselves without departing from the spirit and scope of the invention. My disclosures and the description herein are purely illustrative and are not intended to be in any sense limiting.

What I claim is:

1. In apparatus of the class described, the combination with a shaft, alternating current carrying mains and direct current carrying mains, of rotatable members fixed to said shaft, one for each alternating current carrying main and each having uniformly spaced axially extending segments and a circumferential ring electrically connected to said segments, a brush engaging each of said rings and electrically connected to one of the alternating current carrying mains, two sets of brushes for engaging the segments of each rotatable member, the brushes of each set being connected to one of the direct current carrying mains and alternately related to the brushes of the other adjacent set and arranged to simultaneously engage said adjacent segments, and means for driving said shaft.

2. In apparatus of the class described, the combination with a shaft, alternating current carrying supply mains and direct current carrying means and alternating current carrying output mains, of rotatable members fixed to said shaft, one for each alternating current carrying supply main and each having uniformly spaced axially extending segments and a circumferential ring electrically connected to said segments, a brush engaging each of said rings and electrically connected to one of the alternating current carrying supply mains, two sets of brushes for engaging said segments of each rotatable member, the brushes of each set being connected to one of the direct current carrying mains and alternately related to the brushes of the other adjacent set and arranged to simultaneously engage said adjacent segments, separate rotatable members fixed to said shaft, one for each alternating current carrying out-put main and each having uniformly spaced segments and a ring electrically connected to said segments, a brush engaging each of said last mentioned rings and electrically connected to one of the alternating current carrying out-put mains, two sets of brushes for engaging said last mentioned segments of each of said separate rotatable members, the brushes of each set being connected to one of the direct current carrying mains and alternately related to the brushes of the other adjacent set and arranged to simultaneously engage said adjacent segments, and means for driving said shaft.

3. In apparatus for rectifying alternating current into direct current, the combination with a shaft, alternating current supply mains and direct current leads, of a plurality of commutators fixed to said shaft, one for each supply main and each consisting of a ring surrounding said shaft and having a pair of diametrically related segments and sections of insulation between said segments, a brush engaging each of said rings and connected to one of said supply mains, pairs of uniformly spaced brushes arranged to engage the segments of each commutator, the brushes of each pair being interposed between the brushes of the other pair and connected to one of the direct current carrying leads, and means for rotating said shaft.

4. An apparatus as claimed in claim 3 wherein the shaft rotating means consists of a synchronous motor connected to said alternating current supply mains.

5. In apparatus for rectifying alternating current into direct current, the combination with a shaft, alternating current supply mains and direct current leads, of a plurality of commutators fixed to said shaft, one for each supply main and

each consisting of a ring surrounding said shaft and having a pair of diametrically related segments and sections of insulation between said segments, a brush engaging each of said rings and connected to one of said supply mains, pairs of uniformly spaced brushes arranged to engage the segments of each commutator, the brushes of each pair being interposed between the brushes of the other pair and connected to one of the direct current carrying leads, each brush of each pair having the same angular relation to the axis of said shaft as one of the brushes of the corresponding pair of brushes which engage the segments and insulation sections of each of the remaining commutators, the segments on each commutator being so related to the segments on the remaining commutators angularly of the axis of said shaft that each supply main is connected through one or more commutators with one of the direct current carrying leads except when the phase of said supply main is at zero phase angle, and means for driving said shaft.

6. In apparatus of the class described, the combination with a support and a shaft mounted thereon, of a member consisting of a sleeve formed of insulation material fixed to said shaft, a ring surrounding said sleeve and having a plurality of uniformly spaced segments extending from said ring longitudinally of said shaft and sections of insulation between said segments, a brush mounted on said support and engaging said ring and adapted to be connected to a lead, sets of brushes mounted on said support and uniformly spaced around said shaft, the brushes of each set corresponding in number to the number of segments and arranged to simultaneously engage therewith and each brush of each set being interposed between two brushes of the other set and each adapted to be connected to another lead.

7. In apparatus of the class described, the combination with a support, a shaft mounted thereon, direct current carrying supply mains and two out-put current carrying mains, of a pair of members each consisting of a sleeve formed of insulation material fixed to said shaft, a ring surrounding said shaft and having a plurality of uniformly spaced segments extending from said ring longitudinally of said shaft and sections of insulation between said segments, a brush mounted on said support and engaging each of said rings and connected to one of the out-put mains, sets of brushes mounted on said support and uniformly spaced around the segments of each said member, the brushes of each set corresponding in number to the number of segments and arranged to simultaneously engage therewith and connected to one of the direct current carrying mains, each brush of each set being interposed between two brushes of the other adjacent set, and means for rotating said shaft.

8. In apparatus of the class described, the combination with alternating current carrying in-put mains, direct current carrying mains and alternating current carrying out-put mains, of means for connecting each of said alternating current in-put mains alternately to said direct current mains in co-ordinated relation to the reversal of current flow in said alternating current main and disconnecting the alternating current mains from the direct current mains when the phase angle in the alternating current mains is zero, and separate means for alternately connecting each direct current main to said alternating current out-put mains.

HOWARD I. MORRIS.
